DOOR LOCK

Alberto Schwarz, Lima, Peru

Application October 8, 1934, Serial No. 747,430
In Peru October 17, 1933

1 Claim. (Cl. 70—14)

The invention relates to door locks and has special reference to swinging door locks.

The primary object of the invention is the provision of a lock of this character, wherein the bolt can be manually thrown to a full locking position or to partially locking position, and in the latter position will permit the automatic latching of a swinging door when swung to closed position, the lock being rendered safe from manipulation so that its bolt can be held fast when in locking position, either partially or fully thrown, or in a retracted unlocking position.

Another object of the invention is the provision of a lock of this character, wherein both the lock casing and the keeper for the bolt are so mounted and made secure in place as to prevent the surreptitious detachment, particularly when the door is standing open or the lock is holding the door in a closed position, the lock in its make-up being of novel construction and adaptable for mounting upon a door for swinging movement either to the right hand side or the left hand side or for the opening of the door by a push or pull and also susceptible of use on double doors of the swinging type.

A further object of the invention is the provision of a lock of this character, wherein its mechanism is operable through the use of the standard type of keys, as for example, "Yale" keys, and the key control is had only at the outer side of the door, while the locking mechanism is operable at the inside of the door by manual lever control.

A still further object of the invention is the provision of a lock of this character, wherein the bolt is susceptible of being made fast to avoid any possibility of its operation from the outside of the door, whether with the correct key or not, thus assuring safety against false entry to an enclosure.

A still further object of the invention is the provision of a lock of this character which is simple in construction, thoroughly reliable and effective in its purpose, novel in construction, strong, durable, and inexpensive to manufacture. With these and other objects in view, the invention consists in the features of construction, combination and arrangement of parts as will be hereinafter more fully described in detail, illustrated in the accompanying drawings, which disclose the preferred embodiment of the invention, and pointed out in the claim hereunto appended.

In the accompanying drawings:

Figure 1 is a fragmentary elevation of a door and its door frame, showing the lock constructed

in accordance with the invention applied thereto and in locking position.

Figure 2 is an elevation of the lock with the cover plate of its casing removed and the lock bolt in full thrown position.

Figure 3 is a view similar to Figure 2 showing the bolt of the lock in partly retracted position.

Figure 4 is an edge view of the keeper for the bolt.

Figure 5 is a side elevation of a locking dog 10 employed with the lock.

Figure 6 is a bottom plan view thereof.

Figure 7 is a side elevation of the manually operable control lever for the lock.

Figure 8 is an edge view thereof.

Figure 9 is a bottom plan view of the lock and the keeper bolt.

Figure 10 is an inner face view of the removable cover piece for the lock casing.

Figure 11 is an inner face view of the lock casing showing the cover thereon.

Figure 12 is an edge view of the locking bolt.

Figure 13 is a plan view thereof.

Figure 14 is a plan view of the key operated detent of the lock mechanism.

Figure 15 is an edge view thereof.

Figure 16 is an outer face view of the key receiving part.

Figure 17 is an inner face view thereof.

Figure 18 is a top plan of the same.

Figure 19 is a view similar to Figure 17 showing a side elevation thereof.

Figure 20 is an elevation of one of the securing elements for the casing or keeper of the lock.

Figure 21 is a fragmentary elevation of a modified form of lock showing the bolt in partially thrown position.

Figure 22 is a view similar to Figure 21 showing the bolt in full thrown position.

Similar reference characters indicate corresponding parts throughout the several views in the drawings.

Referring to the drawings in detail, particularly Figures 1 to 20 inclusive, which are illustrative of the preferred embodiment of the lock 45 constituting the present invention, A designates generally the lock casing and B the keeper, respectively, the former being mounted upon a swinging door next to its locking edge and being secured in place by the use of screws 10 and 50 anchoring bolts 11, respectively, the latter being extended only partially through the door and accommodating wedging keys 12 which are received in suitable clearances as provided in the door, so that they are concealed when the door is closed 55

- and thus it is impossible to remove the lock casing A when the door is standing open or is in closed position, which latter is the locking position thereof.
- 5 Formed interiorly of the casing A is a guideway 13 for a sliding locking bolt 14, it having the outer beveled edge or latching end 15, and such bolt may be partially thrown or fully thrown to a locking position and in such position will be received in a slot 16 provided in the edge of the keeper B, which latter is made secure in place by the bolts 17, these being identical to the bolts 11, and such keeper is carried by the door frame or by one of double doors for accommodating the locking bolt. The bolt 14 when in partially thrown position will operate to automatically latch with the keeper B, as will be herein-after fully described.

Suitably fitted in the door for access at the outer side thereof is a rotatable key receiving guide 18 having the key slot 19 which directs a key to the hub 20 of a double acting cam 21, the hub 20 of the key receiving guide 18 being journaled in a cover plate 22 for the casing A. The double acting cam 21 cooperates with a striking lug 23 carried by a manually operable throw lever 24. This throw lever 24 is pivoted, at 25, in its fitting within the casing A and has the finger grip 26 projected exteriorly thereof. The throw lever 24 is provided with the opening 27 accommodating a striker lug 28 on the bolt 14, so that by hand action upon the lever 24 the bolt 14 can be moved. Also, by a key engaged in the hub 20 of the cam 21, said bolt 14 can be moved.

35 Within the casing A is a spring 29 which operates upon the bolt 14 to urge the same to a latching position, the spring being adapted to act directly upon the bolt.

Within the casing A above the guideway for the bolt 14 is a dog or detent 30 pivoted at 31 and acted upon by a spring 32 for urging it into holding position with respect to the bolt 14. This dog or detent 30 carries a beveled tooth or jaw 33 which is designed to engage in the notches 34 and sockets 35, respectively, these being disposed in opposite edges of the bolt 14, and the purpose of which is to permit the bolt to be reversed in the lock casing A in conformity with the direction of the swing of the door to the right hand side or to the left hand side. The dog or detent 30 when engaging the sockets 35 holds the bolt in full thrown position and on the engagement of such dog or detent 30 with the notches 34 the bolt is only partially thrown to locking position, but in this position it will automatically latch with the keeper B due to the formation of the notches 34 and the tooth or jaw 33, respectively.

The lever 24 is provided with opposite cam edges 36 coating with a tongue 37 on the dog or detent 30 so that when the lever 24 is shifted the contact of the cam edge 36 with the tongue 37 lifts the detent or dog from holding position when engaging the bolt 14 with the jaw or tooth 33 fitting the socket 35, the opening 27 in the lever 24 being of a character as to permit the cam action on the dog or detent so that the bolt when in fully thrown position can be retracted for the unlocking of the door or such bolt released from partially retracted position.

Threaded in the bottom edge of the casing A is a set screw 38, its tapered inner end 39 being engageable with a series of seats 40, these being properly spaced from each other and formed in the lower edge of the bolt 14, and the purpose

of this screw is to hold fast the said bolt when in a retracted position, a partially extended position or full stroke locking position and functions as a safety device to avoid key operation of the lock or the lever operation of the same.

The outer face of the casing A has provided thereon the framed spaces 41 for the marking as per the serial number or other identification indicia of such lock.

In Figures 21 and 22 of the drawings there is shown a modification of the lock, wherein the lock, including the casing C and keeper D, respectively, is mounted on double doors of the swinging type, or the same may be mounted on a single door and the frame for the latter, but as an example of mounting the casing C being upon one door and the keeper D upon another of the pair. Arranged within the keeper D is a trigger 42 which is pivoted, at 43, to be normally disposed in the path of movement of the bolt 14 of the lock and this trigger coacts with an actuator rod 44 fitting a guide 45, which rod also serves as a locking bolt and acts upon a weighted lever 46, pivoted, at 47, above the door on the frame therefor. The lever 46 carries a locking bolt or latching extension 48 to engage with a keeper 49 of the other door opposite that carrying the keeper so as to lock this other door at its top edge when closed and on the throwing of the bolt 14 to full locking position in the keeper D.

The keeper D also has extended within the same the actuator member 50, pivoted at 51, and this member is extended in the path of the bolt 14 when in thrown position and carries a locking bolt or latching extension 52 engageable with a keeper 53 on the said other door, so that the latter will be locked at the lower portion thereof. These bolts 48 and latching extensions 52, respectively, play through guides 54 which are located as shown in Figures 21 and 22 of the drawings.

On the full throw of the bolt 14 it will actuate the trigger 42 and the actuator lever member 50 to throw the locking bolts or latching extensions 48 and 52 so that the doors will not only be locked at the point of the lock casing C but also at the upper and lower portions thereof and in this fashion a triple lock is created. When the bolt 14 is retracted to unlocking position the levers 46 and 50, respectively, by reason of their pivotal mounting the bolts 48 and 52 will be automatically moved to releasing position for the complete unlocking of the door. The lock is susceptible of being latched in two positions, that is to say, the bolt 14 namely a half thrown position or full thrown position and in the latter position it can be released through a cam or a manually shiftable lever. The bolt 14 of the lock coacts with latches capable of fastening a door at points remote from the lock, the latches 80 being released when the bolt is either in half thrown position or completely retracted.

What is claimed is:

In a door lock, a casing, a throw bolt guided in the casing, a spring in the casing to partly influence the bolt through the casing, a pivotally supported spring influenced locking dog in the casing having a tooth and having a lateral tongue at the free end thereof, said bolt having a socket and a notch which latter presents a vertical inner wall and a wall at an acute angle thereto and is spaced from said socket and either said socket or said notch designed to receive the tooth of the dog therein in accordance with the length of the throw of the bolt, a double armed 75

lever arranged in the casing along one side of the bolt having a handle end which freely passes through the casing and having its second end provided with a pair of rounded shoulders either 5 of which is designed to contact with the lateral tongue on the locking dog to move said dog away from the bolt when the lever is fully thrown in either of two directions and said lever having an opening, a striker lug on the bolt

received through said opening, a key actuated double cam swingably mounted in the casing, a striker lug on the lever engageable by said cam, and adjustable means carried by the casing movable to engage with the bolt when the latter is 5 in any of its positions for locking the bolt from movement.

ALBERTO SCHWARZ.
